DESIGN FOR A COMBINATION PICTURE FRAME AND FLOWER HOLDER

Maximilian C. Meyer, Brooklyn, N. Y.

Application January 10, 1941, Serial No. 97,961

Term of patent 3½ years

To all whom it may concern:

Be it known that I, Maximilian C. Meyer, a citizen of the United States, residing at Brooklyn, in the county of Kings and State of New York, have invented a new, original, and ornamental Design for a Combination Picture Frame and Flower Holder, of which the following is a specification, reference being had to the accompanying drawing, forming a part thereof.

The characteristic features of my design reside in the combination picture frame and flower holder comprising a substantially flat frame member having off-set from the center a picture receiving opening, in combination with a rope-like ring bracket supporting a conical flower vase off-set from the opening, all as shown in the drawing.

I claim:

The ornamental design for a combination picture frame and flower holder, as shown and described.

MAXIMILIAN C. MEYER.
